(57) **CLAIM**

The ornamental design for a casing for an air conditioning, cooling and/or heating apparatus, as shown and described.

DESCRIPTION

FIG. 1 is a front view of an embodiment of the casing.
FIG. 2 is a back view of an embodiment of the casing.
FIG. 3 is a left-side view of an embodiment of the casing.
FIG. 4 is a right-side view of an embodiment of the casing.
FIG. 5 is a top view of an embodiment of the casing.
FIG. 6 is a bottom view of an embodiment of the casing; and,
FIG. 7 is a perspective view of an embodiment of the casing
showing an ornamental effect.
